(57) **CLAIM**

The ornamental design for a cannula cover as shown and described.

DESCRIPTION

FIG. 1 is a perspective top front right view of a cannula cover, showing my new design;

FIG. 2 is a perspective bottom rear left view thereof;

FIG. 3 is a left elevation view thereof, wherein the right elevation view is a mirror image thereof;

FIG. 4 is a top plan elevation view thereof; and,

FIG. 5 is a bottom plan view thereof.
